UNITED STATES PATENT OFFICE.

EMIL A. NELSON, OF DETROIT, MICHIGAN, ASSIGNOR TO ROTARY VALVE MOTOR COMPANY, OF DETROIT, MICHIGAN, A CORPORATION OF MICHIGAN.

ROTARY VALVE.

1,103,996.

Specification of Letters Patent. Patented July 21, 1914.

Application filed October 13, 1910. Serial No. 586,850.

To all whom it may concern:

Be it known that I, EMIL A. NELSON, a citizen of the United States of America, residing at Detroit, in the county of Wayne and State of Michigan, have invented certain new and useful Improvements in Rotary Valves, of which the following is a specification, reference being had therein to the accompanying drawings.

The invention relates to rotary valves particularly designed for use on explosion engines of the multi-cylinder type, and the invention consists in the construction as hereinafter set forth.

In the drawings, Figure 1 is a longitudinal section partly in elevation through the valve and its case; Fig. 2 is a cross section on line $x-x$ Fig. 1; Fig. 3 is a section on line $y-y$ Fig. 1.

A is the casing of a multi-cylinder explosion engine, B is a valve case integral with the casing A, and C is a rotary valve in the case B. The valve C extends to the various cylinders of the engine and is provided with a series of ports D D' for respectively registering with the ports E of the several cylinders.

To prevent leakage, around the valve and from the ports of one cylinder to another, the clearance between the valve and its seat is reduced to the minimum, and there is also preferably provided means for introducing a lubricant in this clearance space for completing the seal. As shown, the lubricating means employed consists in a channel F extending longitudinally of the valve and having a segmental insert G therein fitted with just sufficient clearance to permit a film of oil to pass from the channel to the valve.

The construction as thus far described will be effective where the machining of the valve and its seat is mechanically perfect and where there is no distortion due to the heating of the metal or from other causes. It has however been found in practice that from one cause or another there is frequently a slight disalignment of the valve and its case, causing portions of the valve to bear with greater pressure upon the adjacent case than other portions. As a result the friction is greatly increased and also the wearing of the metal. The greater the number of cylinders in the construction, the

more this effect will be intensified through 55 the greater length of valve. The present invention is designed to overcome this difficulty by dividing the valve into a plurality of sections with flexible connections therebetween. This will permit each valve section to seat independently of the others and will relieve the stress that would otherwise be developed where the sections of the case are not in perfect alinement with each other. At the same time, the valve is a unit in so 60 far as all the sections are compelled to rotate together and preferably all of said sections are formed integral with the metal intermediate the sections reduced in diameter to form the flexible connection.

As shown, H are annular grooves cut in the valve intermediate the adjacent ports D and D' thereof. These grooves extend inward so as to only leave a sufficient section I to transmit the torque from one section 70 of the valve to another. The rigidity of the connection is however, greatly diminished and will permit a deflection of one section in relation to another by a comparatively slight stress. The amount of deflection necessary to obtain the proper seating of the valve is very slight, seldom exceeding a few thousandths of an inch, and this is easily provided for by the reduced section.

Leakage from the port of one cylinder to 85 an adjacent one is guarded against by the use of packing rings J arranged between adjacent portions of the valve. These rings are preferably located in the groove or channel H and thus a double function is performed by said channel, first, by imparting 90 flexibility to the valve, and second, by forming a recess for the reception of the packing ring.

What I claim as my invention is:

1. The combination with a cylindrical valve case, of a rotary valve therein having a plurality of ported sections, grooves intermediate adjacent sections reducing the area of the cross section to increase the flexibility thereof, and a packing ring engaging 95 said groove.

2. The combination with a cylindrical valve case, of a rotary valve therein having 100 aligned ports in different longitudinal portions thereof registering with coöperating ports in the case, a groove between adjacent ports in said valve reducing the area of 105

cross section to increase the flexibility thereof, and a packing ring engaging said groove.

3. The combination with the valve case of an explosion engine, of a rotary valve there-in having ports in different longitudinal portions thereof, a packing ring positioned intermediate adjacent ports, and a groove in said valve for increasing the flexibility thereof intermediate the adjacent ports and

forming a recess for receiving said packing ring.

In testimony whereof I affix my signature in presence of two witnesses.

EMIL A. NELSON.
